Specification for Design.

Patented May 25, 1920.

Application filed January 23, 1920. Serial No. 353,582. Term of patent 7 years.

To all whom it may concern:

Be it known that I, GEORGE EDWARDS BENNIE, a citizen of the United States, and a resident of Nashville, in the county of Davidson and State of Tennessee, have invented a new, original, and ornamental Design for Tire-Treads, of which the following is a specification, reference being had to the accompanying drawing, forming a part thereof.

Figure 1 is a top plan view of an automobile tire showing my improved design, and

Fig. 2 is a sectional view taken on the line 2—2 of Fig. 1.

I claim:

The ornamental design for a tire tread as shown.

GEORGE EDWARDS BENNIE.
